MACHINE GUN CHARGER

Harry C. Grant, Jr., New York, N. Y., and William A. V. Thomsen, Glen Ridge, N. J., assignors to Specialties Development Corporation, Bloomfield, N. J., a corporation of New Jersey

Application April 10, 1942, Serial No. 438,412

17 Claims. (Cl. 89—1)

The present invention relates to automatic machine guns and the like, and more particularly to improved gun chargers for charging or recocking the charging mechanism of the gun.

In automatic machine guns, for example, of the "Browning" type, the firing pin may be released either mechanically or electrically to fire a cartridge in the barrel or breech of the gun. The recoil caused by the explosion of the cartridge causes a bolt mechanism or charging mechanism to be moved backward or retracted. Upon backward movement, the charging mechanism effects withdrawal of the case of the fired cartridge and moves a cartridge belt to present a succeeding cartridge adapted to be fed into the breech. After the charging mechanism has been fully retracted, it is returned or moved forwardly by a strong spring or the like. In the course of its return stroke the charging mechanism ejects the fired cartridge case and feeds the succeeding cartridge into the breech or barrel.

While the firing pin is released, the gun fires when the charging mechanism returns to its extreme forward position. If no trouble develops, the cycle of operation of the charging mechanism may be repeated at a rate of between about 400 and 1000 times per minute.

Preferably, machine guns of the foregoing type are provided with a device known as a gun charger which is adapted to retract the charging mechanism, in the event the charging mechanism is not retracted or moved backward in its normal manner during the firing of the gun. The gun charger may comprise a pneumatically operated ram or the like adapted to retract and recock the charging mechanism and means, such as a strong spring, for returning the ram to its initial position after operation thereof.

In connection with such gun chargers, it has been found that the charging mechanism has a tendency to follow the ram during its return stroke, whereby the charging mechanism is retarded by the ram and does not develop sufficient inertia to move the cartridge belt one notch or step and effect insertion of a succeeding cartridge into the breech of the gun.

An object of the present invention is to provide an improved gun charging or recocking device which is not subject to the foregoing difficulties.

Another object is to provide a gun charger adapted to permit the charging mechanism to snap back into its forward position without being influenced by any restraining forces.

Another object is to provide a gun charger

which permits the charging mechanism to be returned to its forward position with sufficient momentum to move the cartridge belt, eject an empty cartridge case, and feed a successive cartridge.

Another object is to cause the gun charger to move the charging mechanism toward its retracted position until suitable means for permitting the charging mechanism to snap forward have been rendered effective.

Another object is to accomplish the foregoing objects in a simple and inexpensive manner, and without complicating the manufacture, assembly or operation of the gun charger.

A further object consists in the combination, construction and arrangements of parts, whereby the foregoing objects are accomplished.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawings, forming a part of the specification, wherein:

30 Figure 1 is a diagrammatic side view of a machine gun having a gun charger attached thereto.

Figure 2 is a schematic view of the essential operating parts of the gun charger, illustrating an embodiment of the invention, with the parts shown in set or unoperated position.

Figure 3 is a view similar to Figure 2, with the gun charger shown during its retracting or recocking operation.

Figure 4 is a view similar to Figures 2 and 3, with the gun charger and charging mechanism in fully retracted position.

In accordance with the invention, it has been found that the foregoing objects may be accomplished by providing a gun charger, or the like, having means, such as a ram, adapted to retract the charging mechanism of a machine gun, and having means adapted to prevent the ram from interfering with the charging mechanism during the return stroke of the charging mechanism

50 toward its forward position; whereby the charging mechanism is adapted to snap back and develop sufficient inertia to perform its intended functions.

In the illustrative embodiment, about to be described, these means comprise a device for mo-

mentarily delaying the return of the charging mechanism toward its forward position, thereby enabling the ram to return in advance of the charging mechanism and preventing the charging mechanism from being retarded by the ram. A suitable latching device may be utilized for this purpose which latches the charging mechanism in retracted position when the ram of the charging device has moved the charging mechanism rearwardly and which releases the charging mechanism after the ram of the charging device has returned toward its initial position. The ram, preferably, is operated pneumatically by a pressure medium which is maintained effective to urge the ram toward its rearward position until the charging mechanism has been latched.

Referring to the drawings, and more particularly to Figure 1, there is shown a machine gun, for example, of the "Browning" type which, generally comprises a barrel assembly 8 and a bolt mechanism or charging mechanism 9 (not shown in detail), located in a housing or casing 10. The charging mechanism is of the usual design and comprises a number of slidably movable or reciprocating parts which are adapted to be moved rearwardly or retracted by the recoil resulting from the explosion of cartridges and adapted to be moved forwardly or returned by resilient means, such as a spring 11 or the like. During the reciprocation of these parts, the normal operating cycle of the gun is carried out. This cycle comprises the steps of removing a cartridge from the cartridge belt and inserting it into the barrel, firing the cartridge, withdrawing the empty cartridge case from the barrel, moving the belt one notch, and ejecting the cartridge case from the housing 10. Since the construction and operation of such a charging mechanism is well known to those skilled in the art and since the charging mechanism per se does not constitute a part of the present invention, a detailed illustration and description thereof is not believed to be necessary.

In the event the normal operating or firing cycle of the gun is interrupted and firing ceases, the gun must be recharged or recocked before it will operate automatically again. To accomplish this, a gun charger 12, suitably encased, may be attached to either side of the gun casing or housing 10 and may be operatively connected to the charging mechanism by a bolt or stud 14. The stud or bolt 14 reciprocates with, and may be part of, the charging mechanism, and is adapted to extend through an elongated slot 15 in the housing and extend into the gun charger casing.

The gun charger 12, preferably, is pneumatically operated by a fluid pressure medium, such as high pressure carbon dioxide, compressed air or any suitable gas stored in a container 16. The pressure medium is supplied to the gun charger by a hose or tube 17 connected to a valve 18 which is adapted to be operated by suitable devices (not shown), actuated in response to the failure of the charging mechanism to reciprocate in its normal manner. Suitable electrically operated devices may be utilized for detecting the stoppage or slowing down of the charging mechanism, which may be associated with the charging mechanism and the gun charger. These detecting devices may be electrically connected to a control panel, a source of electrical energy, and other electrical devices by means of a cable 19 containing electrical conductors.

In Figures 2, 3 and 4, a gun charger is shown,

illustrating the essential operating parts with which the present invention is more particularly concerned. The gun charger is provided with a pneumatically operated ram or plunger mechanism 20, comprising a cylinder 21 and a piston assembly 22 slidably mounted in the cylinder. The piston assembly extends out of one end of the cylinder and carries a ramming head 24 (Figure 3) positioned for movement in the path of a rider assembly 25 connected to the reciprocating bolt or stud 14 of the charging mechanism. When the ram is operated, the piston assembly moves out of the cylinder and the ramming head 24 is adapted to engage the rider assembly 25 and move it toward the left, that is, in rearward or retracted position with respect to the gun. The piston assembly and ramming head may be moved into their initial position by resilient means such as a spring 23 (Figure 2). The rider assembly 25 is provided with a latching projection 26 adapted to cooperate with the latching means to be described hereinafter.

The other end of the cylinder 21 is provided with a port 27 for admitting a pressure medium in back of the piston and for permitting the pressure medium to be exhausted. A tube or conduit 29 connects the port 27 to the valve 18, which is adapted to control the admission of the pressure medium to the cylinder 21 and the exhaust of the medium to the atmosphere.

The valve 18 comprises an inlet 30 for attaching the hose 17 supplying the pressure medium from the container 16, a valve seat 31 adjacent the inlet 30, a valve chamber 32, a port 34 in communication with the valve chamber 32 and leading to the tube 29, and an exhaust port or vent 35 in communication with the valve chamber 32 and having an annular seat 36. A suitable valve member 37 is slidably mounted in the valve chamber 32 for controlling the inlet and exhaust of the pressure medium. The valve member 37 has a sealing surface 39 at one end for engaging the valve seat 31 and has a plug shaped portion 40 at the other end adapted to abut the seat 36 of the exhaust port when the surface 39 is unseated.

The pressure medium at the inlet 30 tends to unseat the valve member 37 and drive the portion 40 thereof against the exhaust port seat 36. In order to seat the valve member against the seat 31 and normally close the inlet 30, a slidable stem 41 is mounted in the valve body which has, at one end, a portion 42 of reduced diameter extending through the opening of the seat 36 without sealing the same, which urges the valve member 37 towards the seat 31, and has, at the other end, a head or button portion 44 extending outwardly of the valve body and adapted to be engaged by a lever 45 for urging the stem into the valve body.

The lever 45 has one end thereof pivoted to the valve body at 46, and is provided with a toe 47 adjacent and below the pivot for engaging the head 44 of the valve operating stem. A spring 49 has one end thereof attached to the lever 45 adjacent its free end and the other end of the spring 49 is attached to one end of a lever 50 having its other end pivoted at 51. A stud or roller 52 is mounted adjacent the free end of the lever 50 and is adapted normally to engage an upwardly facing cam surface 54 on the lever 45 adjacent the free end thereof. The spring 49 attached to levers 45 and 50 is tensioned, whereby the roller is adapted to urge the free end of the lever 45 downwardly and cause the toe 47 to

move or maintain the valve operating stem 41 in its inwardly extending position.

Adjacent and below the cam surface 54, and towards the free end of the lever 45, a notch 55 is provided for receiving the roller 52 when the lever 45 is forced upwardly, whereby the roller 52 locks the lever 45 in its upper position, with the toe 47 moved away from the valve operating stem 41 to permit the valve member to be moved from its seat 31 and admit pressure to the cylinder 21. Upward movement of the lever 45 may be effected by a plunger 56 of a solenoid 57 adapted to be actuated when an emergency occurs and it is desired to operate the ram. The solenoid plunger is adapted to be returned to its initial or downward position by a leaf spring 59, or the like.

In order to move the lever 45 downwardly to close the valve, the lever 45 is provided at its free end with a finger 60 adapted to be engaged by a pin 61 mounted on one end of a slidably mounted bar or rod 62. The bar 62 is adapted to be operated, by a spring 64, to cause the lever 45 to close the valve when the latch mechanism, about to be described, has latched the rider assembly 24 in retracted position. The spring 64 has one end thereof attached to the pin 61 and has its other end attached to one arm 65 of a bell crank 66 pivoted at 67 and carrying a roller or stud 69 on the arm 65 which is slidably disposed in a slot 70 formed in the bar 62.

The bell crank 66 serves to tension the spring 64 to cause the spring to move the bar 62 toward the left and also serves to return the bar toward the right when the ram is returned to its initial position. In order to accomplish these functions, the other arm 71 of the bell crank carries a pulley or roller 72 adapted to ride on a track or ridge 74 on the top of the piston assembly 22 of the ram. When the piston assembly is moved out of the cylinder 21, the pulley 72 and the bell crank arm 71 are swung upwardly to rock the bell crank and cause its arm 65 to tension the spring 64 while the roller 69 rides toward the left in the slot 70. Thus, when the bar is released by the latching mechanism, about to be described, the bar moves toward the left under the influence of the spring 64.

A spring 75, stronger than the spring 64, has one end attached to the bell crank arm 65 and is adapted to rock the bell crank into its initial position when the piston assembly is returned under the influence of its spring 23, and, when the pulley 72 drops off the track 74, the roller 69 then rides toward the right in the slot 70, engages the end of the slot, and pulls the bar toward the right into its initial position.

The latch mechanism for latching the charging mechanism in retracted position and momentarily delaying its return until the piston assembly of the ram has returned towards its initial position comprises a fixed bar or upright member 80, a latching member 81, and a lever 82 for preventing the bar 62 from moving toward the left and operating the lever 45 to close the valve 48, until the latching member 81 engages and latches the rider assembly 25 of the charging mechanism.

The latching member 81 is pivoted adjacent the lower end of the upright member 80 at 84, and has a projection or lug 85 at its free end for engaging the latching projection 26 of the rider assembly. The lever 82 is pivoted adjacent the upper end of the member 80 at 86, and has a roller 87 at its free end adapted to engage

the end 89 of the bar 62 and hold the bar against movement toward the left. The latching member 81 is connected to the lever 82 for pivotal movement therewith by a link 90 pivoted to the member 81 at 91, and to the lever 82 at 92.

The lever 82 is adapted to be moved downwardly to release the bar 62 and the latching member 81 is adapted to be moved downwardly into latching position when the ramming head 24 has driven the rider assembly 25 into its fully or extreme retracted position. This is accomplished by a bumper 94 which is pivoted to the upright member 80 at 95 and is provided with a depending finger or arm 96 at its free end adapted to be engaged by the ramming head 24. The bumper 94 is connected to the bar retaining lever 82 by a spring 97, whereby pressure of the ramming head against the bumper causes the free end of the lever 82 to be pulled downwardly. When this occurs, the latching member 81, by reason of the connecting link 90, is also moved downwardly and is caused to latch the rider assembly.

A second spring 99 has one end attached to the bumper 94 and has its other end attached to a fixed point at 100. This spring is normally under tension and causes the bumper to be urged upwardly against a stop 101 on the connecting link 90 to maintain the finger 96 of the bumper in the path of the ramming head 24. The spring 99, by urging the bumper against the stop 101, tends to lift the connecting link and the bar retaining lever 82, whereby the free end of the lever 82 is normally maintained in its upper position and in the path of the bar 62. The spring 99 further serves to absorb the impact due to the ramming head striking the bumper, and prevents the damaging or breaking of the parts of the latching mechanism or the piston assembly.

The strength of the springs 97 and 99 is so adjusted that the latching member 81 must be placed into latching relation before the lever 82 can release the slidable bar 62. In this manner the bar 62, through the connecting linkage, holds the valve open until the rider assembly of the charging mechanism is latched, whereby the valve is closed to permit the piston assembly to return only when the charging mechanism is latched. This prevents the rider from following the ramming head, in engaging relation, during its return or forward stroke. By delaying the unlatching until the piston assembly is returned, the charging mechanism is adapted to snap back with sufficient inertia to put the gun into operation again.

In the normal operation of the machine gun the parts of the gun charger are in the set or unoperated position shown in Figure 2, and the charging mechanism and the rider assembly 25 attached thereto reciprocate at a rate of about 400 to 1000 times per minute. The valve of the container 16 of pressure medium is opened to enable the pressure medium to flow to the valve 18. Valve 18, however, is closed by the lever 45 having its free end urged downward by the lever 50 and its spring 49, whereby the toe 47 of the lever 45 forces the stem 41 inwardly to hold the valve member 37 on its seat 31.

The piston assembly 22 is held in the cylinder 21 of the ram by the spring 23 and the ramming head 24 is out of contact with the rider assembly. The slidable bar 62 is urged toward the right by the bell crank 66 and its spring 75, and the pulley 72 on the bell crank is in its lower position. The latching mechanism is held in ineffective posi-

tion by the springs 97 and 99 which through the connecting linkage hold the locking lug or projection 85 in its upper position and the bar retaining lever 82 in position to prevent movement of the bar 62.

In the event an emergency should occur, that is, should the charging mechanism slow up materially or stop completely, a detecting mechanism actuates certain devices, including a switch adapted to close an electrical circuit for momentarily energizing the solenoid 57. The detecting mechanism and its associated devices are not illustrated and described herein because they do not constitute a part of the present invention.

When the solenoid is energized (Figure 3) the plunger 56 thereof is moved upwardly, in opposition to its spring 59, and raises the valve operating lever 45. As the lever 45 is raised, the toe 47 moves away from the head 44 of the valve operating stem 41, thereby permitting the pressure medium at the valve inlet 30 to unseat the valve member 37 and move the plug shaped portion 49 of the valve member against its seat 36 to close the exhaust port 35. Simultaneously, upon raising the lever 45, the roller 52 on the lever 50 rides off the cam surface 54 and snaps into the notch 55, whereby the lever 45 is maintained in valve opening position under the influence of the spring 49 attached to the lever 50. This arrangement requires that the solenoid be energized only momentarily to raise the lever 45, the plunger 56 thereof being returned by the spring 59.

When the valve 18 has been permitted to open in the foregoing manner, the pressure medium flows through the valve chamber and the tube or conduit 29, and enters the cylinder 21 of the ram in back of the piston assembly 22 to move the piston assembly out of the cylinder, as shown in Figure 3, in opposition to the spring 23. As the piston assembly is projected outwardly from the cylinder the track or ridge 74 of the assembly slides under the roller 72 and raises it, whereby the bell crank 66 supporting the pulley is rocked and the upper arm 65 of the bell crank moves toward the left. The roller 69 on the arm then moves toward the left, in its slot 70; and the spring 64, attached to the arm 65 and to the slideable bar 62, at 61, is tensioned to urge the bar 62 toward the left. However, sliding movement of the bar 62 is prevented by the roller 87 abutting the end 89 of the bar 62.

As the piston assembly continues to move out of its cylinder, the ramming head 24 travels in the path of the rider assembly, until, eventually, the ramming head locates and engages the rider assembly and moves it toward its retracted position. The piston assembly continues to retract the rider assembly and the charging mechanism, to which the rider assembly is connected, until these parts approach the position shown in Figure 4. As the outward stroke of the piston assembly is about to be completed, the ramming head 24 strikes the bumper finger or arm 96 and moves it downwardly to tension the spring 97 which pulls the lever 82 downwardly. The lever 82 in turn moves the latching member 81 downwardly by means of the connecting link 90 so that, upon completion of the retracting stroke, the rider assembly has slid under the latching member and the latching projection 85 thereof is adapted to engage the latching projection 26 of the rider assembly to lock the rider assembly and the charging mechanism in retracted position.

When the lever 82 is moved downwardly it moves the roller 87 at its free end out of abutting relation with the end 89 of the slideable bar 62, whereupon the bar is released and the spring 64 moves the bar toward the left and over the roller 87 to hold down the lever 82. In the event the ramming head does not move the bumper properly to effect latching of the rider assembly, the lever 82 restrains the bar 62. The valve then continues to be held open until the ramming head is properly driven against the bumper to effect latching.

When the lever 62 is moved toward the left, the pin 61 strikes the finger 60 of the valve operating lever 45 and moves the lever 45 downwardly to permit the roller 52 to ride out of the notch 55 and into engagement with the cam surface to again tend to hold the lever 45 in valve closing position. The toe 47 now urges the valve operating stem inwardly to cause the valve member 37 to close the inlet of the valve and to open the outlet vent or exhaust port.

The pressure medium in the cylinder 22 is then adapted to be exhausted, and the spring 23 pulls the piston assembly forwardly with respect to the gun, or towards the right as indicated in the drawings, to return it toward its initial position. While the piston assembly is being returned, and as long as the pulley 72 is supported by the track 74, the bar 62 serves to hold down the lever 82 and maintain the member 81 in latching relation with the rider assembly. However, when the piston assembly approaches its initial position and track 74 has moved from under the pulley (Figure 2), the pulley 72 is free to move downwardly and the spring 75 is effective to rock the bell crank, whereby the upper arm 65 thereof moves toward the right. The roller 69 on the arm 65 now rides in the slot 70 toward the right and is effective to pull the bar 62 toward the right to release the lever 82. As this occurs the springs 97 and 99 operate the latching mechanism to cause the latching member 81 to release the rider assembly 24, whereby the spring 11 (Figure 1), associated with the charging mechanism 9, is effective to snap the charging mechanism toward the right or into forward or firing position.

By first moving the piston assembly into its cylinder and out of the path of the rider assembly while the rider assembly remains latched, the spring 11 imparts sufficient momentum or inertia to the charging mechanism 9 in its forward travel to snap it forwardly to perform its charging or gun loading functions. After the gun charger 12 has been operated in the foregoing manner, the gun is cleared and is adapted to operate normally until another emergency occurs. The cycle of operation of the gun charger is completed in a fraction of a second, whereby a minimum amount of time is required to return the machine gun to action.

From the foregoing description it will be seen that the present invention provides a rapidly operating mechanism for improving the operation of machine gun charges and the like. The parts of the mechanism are simple in design and can be easily manufactured and assembled. The mechanism is rugged in construction and can readily withstand any rough usage to which it may be subjected.

While the present invention has been described in connection with a gun charger adapted to operate in an emergency to place the gun into firing operation again, it will be understood that

the gun charger may also be utilized to start the firing operation of the gun. Thus, in the foregoing description and in the appended claims, the term "emergency" is intended to include all situations arising in connection with the use of the gun where it is desired to mechanically retract the charging mechanism by operation of the gun charger.

As various changes may be made in the form, construction and arrangement of the parts herein, without departing from the spirit and scope of the invention and without sacrificing any of its advantages, it is to be understood that all matter herein is to be interpreted as illustrative and not in any limiting sense.

It is also to be understood that the following claims are intended to cover all the generic and specific features of the invention herein described, and all statements of the scope of the invention which, as a matter of language, might be said to fall therebetween.

We claim:

1. In a gun charger for a machine gun having a reciprocating member adapted to be moved rearwardly by the recoil of the gun and adapted to be moved forwardly by spring means, the combination of: a pressure operated ram adapted to engage the reciprocating member and move it rearwardly; a pivotally mounted latching finger adapted to be located adjacent the reciprocating member when the reciprocating member is in rearward position and adapted to engage and retain the reciprocating member in its rearward position; a pivotally mounted lever adjacent said latching finger; a link pivotally connected to said lever and to said latching finger and having a projection thereon; a bumper pivotally mounted intermediate said latching finger and said lever, said bumper having a portion engaging said projection and having a portion extending into the path of and adapted to be engaged by said ram; a spring for urging said bumper against said projection; a second spring connected to said bumper and said lever arranged to move said lever from one position to a second position when said ram engages said bumper; a bar member for latching said lever in its second position, said bar member having a slot therein; a bell crank pivotally mounted adjacent said ram, said bell crank having an arm arranged to be engaged by said ram when operated to rock said bell crank, said bell crank having a second arm provided with a projection positioned in said slot; a spring connected to said second bell crank arm and to said bar member for moving said bar member into lever latching position, and means connected to said second bell crank arm for urging said first bell crank arm into the path of said first means and for effecting movement of said bar member to unlatch said lever when said first bell crank arm is disengaged by said first means.

2. In a gun charger for a machine gun having a reciprocating member adapted to be moved rearwardly by the recoil of the gun and adapted to be moved forwardly by spring means, the combination of: means adapted to engage the reciprocating member and move it rearwardly; a pivotally mounted latching finger adapted to be located adjacent the reciprocating member when the reciprocating member is in rearward position and adapted to engage and retain the reciprocating member in its rearward position; a pivotally mounted lever adjacent said latching finger; a link pivotally connected to said lever and to said latching finger and having a projection thereon; a bumper pivotally mounted intermediate said latching finger and said lever, said bumper having a portion engaging said projection and having a portion extending into the path of and arranged to be engaged by said first means; a spring for urging said bumper against said pro-

thereon; a bumper pivotally mounted intermediate said latching finger and said lever, said bumper having a portion engaging said projection and having a portion extending into the path of and arranged to be engaged by said first means; a spring for urging said bumper against said projection; a second spring connected to said bumper and said lever arranged to move said lever from one position to a second position when said first means engages said bumper; a bar member for latching said lever in its second position, said bar member having a slot therein, a bell crank pivotally mounted adjacent said first means, said bell crank having an arm arranged to be engaged by said ram when operated to rock said bell crank, said bell crank having a second arm provided with a projection positioned in said slot; means connected to said second bell crank arm and to said bar member for moving said bar member into lever latching position, and means connected to said second bell crank arm for urging said first bell crank arm into the path of said first means and for effecting movement of said bar member to unlatch said lever when said first bell crank arm is disengaged by said first means.

3. In a gun charger for a machine gun having a reciprocating member adapted to be moved rearwardly by the recoil of the gun and adapted to be moved forwardly by spring means, the combination of: means adapted to engage the reciprocating member and move it rearwardly; a pivotally mounted latching finger adapted to engage and retain the reciprocating member in its rearward position; a bumper pivotally mounted adjacent said latching finger having a portion extending into the path of and arranged to be engaged by said first means; linkage means operatively connecting said bumper and said latching finger; a bar member for latching said linkage means, said bar member having a recess therein; a bell crank pivotally mounted adjacent said first means, said bell crank having an arm arranged to be engaged by said first means when operated to rock said bell crank, said bell crank having a second arm provided with a projection positioned in said recess, a spring connected to said second bell crank arm and to said bar member for moving said bar member into linkage means latching position, and a spring connected to said second bell crank arm for urging said first bell crank arm into the path of said first means and for effecting movement of said bar member to unlatch said linkage means when said first bell crank arm is disengaged by said first means.

4. In a gun charger for a machine gun having a reciprocating member adapted to be moved rearwardly by the recoil of the gun and adapted to be moved forwardly by spring means, the combination of: means adapted to engage the reciprocating member and move it rearwardly; a pivotally mounted latching finger adapted to be located adjacent the reciprocating member when the reciprocating member is in rearward position and adapted to engage and retain the reciprocating member in its rearward position; a pivotally mounted lever adjacent said latching finger; a link pivotally connected to said lever and to said latching finger and having a projection thereon; a bumper pivotally mounted intermediate said latching finger and said lever, said bumper having a portion engaging said projection and having a portion extending into the path of and arranged to be engaged by said first means; a spring for urging said bumper against said pro-

jection, a second spring connected to said bumper and said lever and being arranged to move said lever from one position to a second position when said first means engages said bumper; and a member operable by said first means for latching said lever in its second position.

5. In a gun charger for a machine gun having a reciprocating member adapted to be moved rearwardly by the recoil of the gun and adapted to be moved forwardly by spring means, the combination of: means adapted to engage the reciprocating member and move it rearwardly, a latching finger adapted to engage and retain the reciprocating member in its rearward position; a bumper pivotally mounted adjacent said latching finger and having a portion extending into the path of and arranged to be engaged by said first means; linkage means operatively connecting said bumper and said latching finger to render said latching finger effective for retaining the reciprocating member when said bumper is engaged by said first means; a member for latching said linkage means; and lever means operatively connected to said latching means and mounted adjacent said first means and arranged to be engaged by said first means when operated to effect latching of said linkage means by said member and to effect unlatching of said linkage means by said member when disengaged by said first means.

6. In a gun charger for a machine gun having a reciprocating member adapted to be moved rearwardly by the recoil of the gun and adapted to be moved forwardly by spring means, the combination of: means adapted to engage the reciprocating member and move it rearwardly; a latching member adapted to engage and retain the reciprocating member in its rearward position; a bumper member movably mounted adjacent said latching member and having a portion extending into the path of and arranged to be engaged by said first means; linkage means operatively connecting said bumper member and said latching member; said bumper member, upon being engaged by said first means, being arranged to effect positioning of said latching member to engage the reciprocating member; and means operable by said first means for latching said linkage means to cause said latching member to retain the reciprocating member in latched position.

7. In a gun charger for a machine gun having a reciprocating member adapted to be moved rearwardly by the recoil of the gun and adapted to be moved forwardly by spring means, the combination of: means adapted to engage the reciprocating member and move it rearwardly; a latching member adapted to engage and retain the reciprocating member in its rearward position; a bumper member movably mounted adjacent said latching member and mounted for movement independently of said first means and having a portion extending into the path of and arranged to be engaged by said first means; and linkage means operatively connecting said bumper member and said latching member; said bumper member, upon being engaged by said first means, being arranged to effect positioning of said latching member to engage the reciprocating member.

8. In a gun charger for a machine gun having a reciprocating member adapted to be moved rearwardly by the recoil of the gun and adapted to be moved forwardly by spring means, the combination of: a pressure operated ram adapted to move the reciprocating member into its rearward

position; mechanism for latching the reciprocating member in its rearward position; a valve for controlling the admission of pressure medium to operate said ram; a lever having one end pivotally mounted adjacent said valve for controlling the opening and closing of said valve, said lever having a cam surface and a notch adjacent said cam surface, and having a finger at its other end, a pivotally mounted locking lever having a projection arranged to engage said cam surface and enter said notch; a spring connected to said locking lever for moving said projection against said cam surface and into said notch; means for rocking said first lever into valve opening position and to cause said projection to move into said notch to lock said first lever in valve opening position; and means associated with said latching mechanism and operative, when said latching mechanism is effective to latch the reciprocating member, to engage said finger and move said first lever out of its locked position into valve closing position, whereby said spring moves said locking lever into a position to cause said projection to be moved out of said notch and moved into cam surface engaging position to maintain said first lever in valve closing position.

9. In a gun charger for a machine gun having a reciprocating member adapted to be moved rearwardly by the recoil of the gun and adapted to be moved forwardly by spring means, the combination of: a pressure operated ram adapted to move the reciprocating member into its rearward position; mechanism for latching the reciprocating member in its rearward position; a valve for controlling the admission of pressure medium to operate said ram; a lever having one end pivotally mounted adjacent said valve for controlling the opening and closing of said valve, said lever having a finger at its other end; means for moving said lever into valve opening position; a pivotally mounted locking lever arranged to engage and retain said first lever in valve opening position and means associated with said latching mechanism operative when said latching mechanism is effective to latch the reciprocating member to engage said finger and move said first lever out of its retained position into valve closing position.

10. In a gun charger for a machine gun having a reciprocating member adapted to be moved rearwardly by the recoil of the gun and adapted to be moved forwardly by spring means, the combination of: a pressure operated ram adapted to move the reciprocating member into its rearward position; mechanism for latching the reciprocating member in its rearward position; a valve for controlling the admission of pressure medium to operate said ram; a lever having one end pivotally mounted adjacent said valve for controlling the opening and closing of said valve, said lever having a finger at its other end; a pivotally mounted locking lever arranged to engage said first lever and retain it in valve opening position; and means associated with said latching mechanism operative, when said latching mechanism is effective to latch the reciprocating member, to engage said finger and move said first lever out of its retained position into valve closing position.

11. In a gun charger for a machine gun having a reciprocating member adapted to be moved rearwardly by the recoil of the gun and adapted to be moved forwardly by spring means, the combination of: a pressure operated ram adapted to move the reciprocating member into its rearward

position; mechanism for latching the reciprocating member in its rearward position; a valve for controlling the admission of pressure medium to operate said ram; a lever pivotally mounted adjacent said valve for controlling the opening and closing of said valve; means for maintaining said lever in valve opening position; and means associated with said latching mechanism operative, when said latching mechanism is effective to latch the reciprocating member, to render said last mentioned means ineffective and move said lever into valve closing position.

12. In a gun charger for a machine gun having a reciprocating member adapted to be moved rearwardly by the recoil of the gun and adapted to be moved forwardly by spring means, the combination of: a pressure operated ram adapted to move the reciprocating member into its rearward position; mechanism for latching the reciprocating member in its rearward position in response to operation of said ram; a normally closed valve for controlling the admission of pressure medium to operate said ram; means for opening said valve and maintaining said valve in an open position to permit pressure medium to operate said ram; and means associated with said latching mechanism operative to render said last mentioned means ineffective in response to said latching mechanism being effective to latch the reciprocating member.

13. In a gun charger for a machine gun having a reciprocating member adapted to be moved rearwardly by the recoil of the gun and adapted to be moved forwardly by a spring, the combination of: means adapted to move the reciprocating member into its rearward position; mechanism for latching the reciprocating member in its rearward position in response to operation of said first means; means for controlling the operation of said first means said controlling means normally being ineffective; means for rendering and maintaining said controlling means effective; and means associated with said latching mechanism operative to render said controlling means ineffective in response to said latching mechanism being effective to latch the reciprocating member.

14. In a gun charger for a machine gun having a reciprocating member adapted to be moved rearwardly by the recoil of the gun and adapted to be moved forwardly by spring means, the combination of: a pressure operated ram adapted to engage the reciprocating member and move it rearwardly; a pivotally mounted latching finger adapted to be located adjacent the reciprocating member when the reciprocating member is in rearward position and adapted to engage and retain the reciprocating member in its rearward position; a pivotally mounted lever adjacent said latching finger; a link pivotally connected to said lever and to said latching finger and having a projection thereon; a bumper pivotally mounted intermediate said latching finger and said lever, said bumper having a portion engaging said projection and having a portion extending into the path of and arranged to be engaged by said ram; a spring for urging said bumper against said projection; a second spring connected to said bumper and said lever and arranged to move said lever from one position to a second position when said ram engages said bumper; a bar member for latching said lever in its second position, said bar member having a slot therein; a bell crank pivotally mounted adjacent said ram, said bell crank having an arm arranged to be engaged by said

ram when operated to rock said bell crank, said crank having a second arm provided with a projection positioned in said slot; a spring connected to said second bell crank arm and to said bar member for moving said bar member into lever latching position; a spring connected to said second bell crank arm for urging said first bell crank arm into the path of said ram and for effecting movement of said bar member to unlatch said lever when said first bell crank arm is disengaged by said ram; a valve for controlling the admission of pressure medium to operate said ram; a lever having one end pivotally mounted adjacent said valve for controlling the opening and closing of said valve, said lever having a cam surface and a notch adjacent said cam surface and having a finger at its other end; a pivotally mounted locking lever having a pin adapted to engage said cam surface and said notch; a spring connected to said locking member for urging its pin against said cam surface and into said notch; means for rocking said valve controlling lever into valve opening position and to cause said pin to ride into said notch to lock said valve controlling lever in valve opening position; and a pin on said bar member arranged to engage said finger of said valve controlling lever to move said valve controlling lever into valve closing position.

15. In a gun charger for a machine gun having a reciprocating member adapted to be moved rearwardly by the recoil of the gun and adapted to be moved forwardly by spring means, the combination of: a pressure operated ram adapted to engage the reciprocating member and move it rearwardly; a pivotally mounted latching finger adapted to be located adjacent the reciprocating member when the reciprocating member is in rearward position and adapted to engage and retain the reciprocating member in its rearward position; a bumper pivotally mounted adjacent said latching finger and having a portion extending into the path of and arranged to be engaged by said ram; linkage means operatively connecting said bumper and said latching finger; a bar member for latching said linkage means; a member mounted adjacent said ram and arranged to be engaged by said ram when operated to control the movement of said bar member into linkage means latching position; spring means for moving said bar member to unlatch said linkage means when said last mentioned member is disengaged by said ram; a valve for controlling the admission of pressure medium to operate said ram; a lever having one end pivotally mounted adjacent said valve for controlling the opening and closing of said valve, a pivotally mounted locking lever for maintaining said valve controlling lever in valve opening position and means on said bar member arranged to render said locking lever ineffective.

16. In a gun charger for a machine gun having a reciprocating member adapted to be moved rearwardly by the recoil of the gun and adapted to be moved forwardly by spring means, the combination of: a pressure operated ram adapted to engage the reciprocating member and move it rearwardly; a pivotally mounted latching finger adapted to be located adjacent the reciprocating member when the reciprocating member is in rearward position and adapted to engage and retain the reciprocating member in its rearward position; a bumper pivotally mounted adjacent said latching finger and having a portion extending into the path of and arranged to be engaged

by said ram; linkage means operatively connecting said bumper to said latching finger; said bumper, upon being engaged by said ram, being arranged to effect positioning of said latching finger to engage the reciprocating member; a member for latching said linkage means to maintain said latching finger in position to retain the reciprocating member in its rearward position; a valve for controlling the admission of pressure medium to operate said ram; means for controlling the opening and closing of said valve; means for maintaining said valve controlling means in valve opening position; and means associated with said latching member for rendering said last mentioned means ineffective.

17. In a gun charger for a machine gun having a reciprocating member adapted to be moved rearwardly by the recoil of the gun and adapted to be moved forwardly by spring means, the combination of: means adapted to engage the reciprocating member and move it rearwardly; a

5 latching finger adapted to engage and retain the reciprocating member in its rearward position; a bumper member movably mounted adjacent said latching finger and having a portion extending into the path of and arranged to be engaged by said first means; linkage means operatively connecting said bumper and said latching finger; said bumper member, upon being engaged by said first means, being arranged to effect positioning of said latching finger to engage the reciprocating member; a member for latching said linkage means to maintain said latching finger in position to retain the reciprocating member; means for controlling the operation of said first means; means for maintaining said controlling means in operating position; and means associated with said latching member for rendering said last mentioned means ineffective.
